UNITED STATES PATENT OFFICE.

WILLIAM F. GOULD, OF DES MOINES, IOWA.

RAILWAY-TIE PLATE.

SPECIFICATION forming part of Letters Patent No. 777,253, dated December 13, 1904.

Application filed October 2, 1903. Serial No. 175,443. (No model.)

To all whom it may concern:

Be it known that I, WILLIAM F. GOULD, a citizen of the United States, residing at Des Moines, in the county of Polk and State of Iowa, have invented certain new and useful Improvements in Railway-Tie Plates, of which the following is a specification.

This invention relates to that class of tie-plates in which the rail-engaging surface is tapered or inclined from its outer to its inner end for the purpose of tilting the top of the rails inwardly.

My objects are to provide a railway-tie plate of this class having longitudinal rail-rests elevated above the surface of the plate and so arranged that after considerable use and wear has taken place a new rail having a wider flange may be placed on the plate and lie flat upon the top of the raised rail-rests. When a rail is placed on top of a smooth-surfaced tie-plate and after considerable wear has taken place, a rail with a wider flange placed on the same plate would partially overlap the unworn portion of the plate, and hence would not lie flat upon the whole rail-supporting surface of the plate.

A further object is to provide a tapered plate susceptible of being changed from one rail to the other of a track and of being used either beneath the angle-bars at the railway-rail joints or throughout the length of the rail itself—that is to say, a single plate is provided having only two spike-openings, which may be used for any of the above-described purposes.

A further object is to provide a tie-plate having ribs on its under surface to enter a tie and shaped to interlock with the wood fibers in such a way as to prevent upward movement of the tie-plate relative to the tie; and a further object is to provide an invertible tie-plate having raised rail-rests on each side so shaped as to sink into a tie and to cover and protect the broken fibers of the wood of the tie at the points where they turn upwardly at the edges of the rail-rests.

My invention consists in certain details in the construction, arrangement, and combination of the various parts of the tie-plate whereby the objects above contemplated are

attained, as hereinafter more fully set forth, pointed out in my claims, and illustrated in the accompanying drawings, in which—

Figure 1 shows a side view of my preferred form of tie-plate resting upon a tie and having a rail supported thereon and angle-bars connected with the rail and spikes for holding the rail and tie-plate to the tie and also by dotted lines showing the position of the various parts when a rail having a wider flange is placed on the same tie-plate. Fig. 2 shows in perspective my preferred form of tie-plate. Fig. 3 shows in perspective a modified form of same. Fig. 4 shows a side view of the plate illustrated in Fig. 3, the ribs thereon being provided with openings to receive the fibers of a tie. Fig. 5 shows an edge view of the form of another modified form of my improved tie-plate with a rail and angle-bars resting thereon and held in position by spikes. Fig. 6 shows a similar view with the plate inverted and the angle-bars omitted; and Fig. 7 shows a plan view of a part of a railway-rail resting on ties, showing two of my improved plates supporting the rail and the angle-bars at the ends of two abutting rails and also showing a similar tie-plate inverted supporting the rail itself.

Referring to Figs. 1 and 2 of the accompanying drawings, my preferred form of tie-plate comprises a flat body portion having on each surface two parallel raised rail-rests extending longitudinally of the rail. The outer rail-rest (indicated by the numeral 10) is of greater thickness than the inner one, 11, and between these rail-rests is a longitudinal channel 12. At the outer edge of the outer rail-rest is a curved inwardly-inclined shoulder 13, and at the inner end of the inner rest is a similar shoulder 14. Beyond the rail-rest 10—that is to say, at the outer end of the tie-plate—is an extension 15, having a tapered edge 16 and a spike-opening 17, the inner edge of the spike-opening being flush with the outer edge of the rail-rest 10. At the inner end of the tie-plate is an extension 18, having a tapered edge 19 and a spike-opening 20. This spike-opening is materially longer than is necessary for an ordinary spike, so that a spike may be driven through the opening 20 close

to shoulder 14 or at some distance from said shoulder.

In practical use with my preferred form of tie-plate I preferably provide a rail having a flange wide enough to completely cover both the inner and the outer rail-rests. These plates are then placed upon a tie, and the rail-rests on the under surface thereon are forced into the tie, resulting in the breaking of the tie fibers at the edges of the rail-rests and also at the ends of the plate. These broken fibers usually stand at or near a vertical position, leaving a broken spongy mass of wood. At these points the extensions 15 and 18 obviously serve to cover the broken fibers at the outer and inner corners of the rail-rests, and the tapered ends 16 and 19 serve to cover the fibers at the ends of the plate, thus serving to protect the broken and spongy mass of wood, so that it will not easily rot or decay. Assuming that the rail has a flange just wide enough to cover the rail-rests, it is obvious that angle-bars may be placed on the rail and the spikes may be driven through the notches in the angle-bars and through the openings in the plate into the tie, and these spikes will rest against both edges of the rail, thus firmly holding the rail against lateral movement. Obviously this tie-plate may be readily inverted, and the upper surface will present a new wearing-surface to the rail. If it is desired to use a rail having a wider flange, the rail is placed in position, and the elongated spike-hole 20 provides means by which the inner spike may be set close against a rail of any ordinary width, and even though considerable wear has taken place on the rail-rests there will be no shoulders left upon the rail-rests at the edges of the rail, as would be the case if the rail rested upon a smooth-surfaced tie-plate. Furthermore, by thus providing two parallel longitudinal rail-rests with a comparatively wide channel between them the central portion of the rail-flange may spring downwardly when a heavy train passes over the rail, thus allowing a considerable elasticity or spring in the rail itself without effecting or having any tendency to spring the tie-plate.

In the modified form illustrated in the remaining figures of the drawings I have shown a tapered tie-plate having at its top a longitudinal rail-rest 21 near its outer end, and in the outer edge of said rail-rest is a rib 22, projecting upwardly above the rail-rests. Near the inner end of the tie-plate is a second rail-rest, 23, parallel with the first, and a channel 24 is provided between them. At the outer edge of the plate is an extension 25, in which the spike-opening 26 is provided, and on the inner edge of the plate is an extension 27, having a spike-opening 28 adjacent to the inner edge of rail-rest 23. The opposite surface of the tie-plate is smooth and flat, and the opposite surface of the extension 25 is provided with a longitudinal rib 29 near its outer edge—

that is to say, beyond the spike-opening 26. The ends of this rib 29 are inclined inwardly toward the plate at 30, and near the central portion thereof is a transverse opening 21. In practical use with this form of my tie-plate and referring to Fig. 5 of the drawings it is obvious that the plate is attached for use under a rail-joint having angle-bars. When applied at the angle-bars, the plate is used with its flat surface uppermost, and in this position the outer edge of the angle-bar rests against rib 29, and the spike passes through the notches in the outer edge of the outer angle-bar and against the rail. Obviously these plates could be used on either one of the two parallel track-rails and either of the rails would be inclined inwardly. Assuming that it is desired to use the tie-plates upon the rails proper without the angle-bars, I then invert the tie-plate, so that the longitudinal rail-rests are uppermost in this position. The outer edge of the rail rests against shoulder 22, and the spike passes through the spike-hole 26 and engages the edge of the rail.

Having thus described my invention, what I claim, and desire to secure by Letters Patent of the United States therefor, is—

1. A reversible tapered tie-plate.
2. A reversible tapered tie-plate formed with a rib on each surface.
3. A reversible tapered tie-plate formed with a rib on each surface out of vertical alinement with each other.
4. An invertible tie-plate having a tapered rail-rest on one surface and also having a rib on one surface to engage a rail on the tie-plate and a rib on the opposite surface to engage an angle-bar, the said tie-plate provided with a spike-opening between said ribs.
5. An invertible tie-plate having tapered rail-rests on both surfaces, and also having a rib on one surface, and a rib on the other surface out of vertical alinement with the first rib, said plate provided with a spike-opening between said ribs.
6. A tie-plate having a rib on one surface to engage the edge of a rail, and a rib on its other surface to engage the edge of an angle-bar on a rail, said tie-plate having a spike-opening between said ribs.
7. A tie-plate having two parallel rail-rests above the surface of the tie-plate, with a channel between them, said rail-rests designed to lie wholly beneath a rail on the tie-plate, the outer rail-rest higher than the inner one.
8. A tie-plate having on each side two parallel rail-rests projecting from the surface of the tie-plate and having a channel on each side between each pair of rail-rests.
9. A tie-plate having two parallel rail-rests on each side, projecting beyond the surface of the tie-plate, each pair of rail-rests having a channel between them, and said rail-rests designed to lie wholly beneath a rail placed on the tie-plate.

10. A tie-plate having two parallel rail-rests on each side projecting beyond the surface of the tie-plate, each pair having a channel between them and said rail-rests designed to lie wholly beneath a rail placed on the tie-plate, the outer rest on each side of greater thickness than the inner one. 5
11. A tie-plate having two parallel rail-rests on each side projecting beyond the surface of the tie-plate, each pair having a channel between them, said rail-rests designed to lie wholly beneath a rail placed on the tie-plate, said tie-plate also having a spike-hole beyond the outer rail-rests, and a spike-hole beyond 10 the inner rail-rests, said spike-holes arranged diametrically opposite each other.
12. A tie-plate having two parallel rail-rests on each side projecting beyond the surface of the tie-plate, each pair having a channel between them and designed to lie wholly beneath a rail placed on the tie-plate, the outer rail-rests on each side of greater thickness than the inner ones, said tie-plate also having a spike-hole beyond the outer rail-rests and 15 a spike-hole beyond the inner rail-rest, said spike-holes arranged diametrically opposite each other. 25
13. A tie-plate tapered from its outer to its inner end, and having a longitudinal rib on one face to engage the edge of a rail-flange 30 and also having a longitudinal rib on its other face to engage the edge of an angle-bar, said ribs out of vertical alinement with each other, and said tie-plate having a spike-opening between the ribs. 35
14. A tie-plate having a rib on one surface near the outer end of the tie-plate and also having a rib on the opposite surface a material distance nearer the outer end of the tie-plate than the first rib, said tie-plate having 40 a spike-opening between said ribs near one corner of the tie-plate and also having a spike-opening at the diametrically opposite corner from the first spike-opening.
15. A tie-plate having a rib to enter a tie, 45 the ends of the rib inclined inwardly from its lower edge toward the tie-plate.
16. A tie-plate having a rib to enter a tie, said rib provided with an opening to receive the broken fibers of a tie.
